(57) **CLAIM**

The ornamental design for a portable speaker, as shown and described.

DESCRIPTION

FIG. 1 is a perspective view of a portable speaker in an expanded state in an embodiment.

FIG. 2 is a front view of the portable speaker in an expanded state showing our new design in an embodiment.

FIG. 3 is a bottom view of the portable speaker in an expanded state showing our new design in an embodiment.

FIG. 4 is a back view of the portable speaker in an expanded state showing our new design in an embodiment.

FIG. 5 is a top view of the portable speaker in an expanded state showing our new design in an embodiment.

FIG. 6 is a left side view of the portable speaker in an expanded state showing our new design in an embodiment.

FIG. 7 is a right side view of the portable speaker in an expanded state showing our new design in an embodiment.

FIG. 8 is a perspective view of a portable speaker in a collapsed state in an embodiment.

FIG. 9 is a front view of the portable speaker in a collapsed state showing our new design in an embodiment.

FIG. 10 is a bottom view of the portable speaker in a collapsed state showing our new design in an embodiment.

(Continued)

FIG. 11 is a back view of the portable speaker in a collapsed state showing our new design in an embodiment. FIG. 12 is a top view the portable speaker in a collapsed state showing our new design in an embodiment. FIG. 13 is a left side view of the portable speaker in a collapsed state showing our new design in an embodiment; and, FIG. 14 is a right side view of the portable speaker in a collapsed state showing our new design in an embodiment. The broken lines shown are included for the purpose of illustrating portions of the portable speaker that form no part of the claim.

1 Claim, 8 Drawing Sheets
